UNITED STATES PATENT OFFICE.

HORACE L. BREWER, OF CAMDEN, NEW JERSEY, ASSIGNOR TO MODERN SAFETY GAS IRON COMPANY, OF PHILADELPHIA, PENNSYLVANIA, A CORPORATION OF DELAWARE.

GAS-HEATED IRON.

1,083,238.

Specification of Letters Patent. Patented Dec. 30, 1913.

Application filed May 17, 1913. Serial No. 768,246.

To all whom it may concern:

Be it known that I, HORACE L. BREWER, a citizen of the United States, and a resident of Camden, Camden county, New Jersey, have invented certain Improvements in Gas-Heated Irons, of which the following is a specification.

My invention relates to irons of the type having self-contained heating means; and the object of my invention is to provide a structure simple in construction and mode of operation, having means insuring the distribution of heat at the points desired, with ample provision for ventilation and the supply of air to the interior thereof.

A further object of my invention is to provide a structure that will be relatively cool adjacent the handle. And a still further object is to provide such an iron with an improved burner designed to be safe under all conditions, and with an improved gas-controlling valve so constructed as to prevent cutting off the supply of gas to the burner before the main valve is closed.

These and other features of my invention will be more fully described hereinafter, reference being had to the accompanying drawings, in which:

Figure 1, is a longitudinal sectional elevation on the line 1—1, Fig. 2, of a gas heated iron having and containing the improvements forming the subject of my invention; Fig. 2, is a sectional plan view on the line 2—2, Fig. 1; Fig. 3, is a cross sectional view on the line 3—3, Fig. 1; Fig. 4, is a sectional view of the burner, slightly enlarged, taken on the line 4—4, Fig. 1; Fig. 5, is a perspective view of the flame deflector; Fig. 6, is a sectional view of the gas supply or burner tube carried by the iron and the valve controlling the supply of gas to the iron, and Fig. 7, is a cross-sectional view on the line 7—7, Fig. 6.

In the drawings, 1 represents the body of the iron, which may be cast hollow and is in a single piece; said body having a series of perforations 2 in its walls 3 extending substantially the length of the iron and disposed adjacent the top of the same, and at the rear a plurality of apertures 4 which open through said walls 3 of the iron into the chamber thereof adjacent the bottom of the same in the form of semicircles; recesses

within the walls of the iron forming said apertures being circular so that there will be no undue trouble or expense in providing the semicircular apertures piercing the wall of the iron.

The iron is provided with the usual handle 5, which may be secured thereto by screws 6; spacing nuts or washers 7 being interposed between the lower portion of the handle and the body of the iron.

Within the iron is a heat or flame deflector 8, which extends substantially throughout the inner chamber of the same and has a forward end 8^a which is bent or curved downward slightly so as to deflect the desired quantity of heat into the toe of the iron, and this deflector may be held in place by means of a screw 11 passing through the top wall of the iron and engaging a recess 12 formed in the top of said deflector. The front end or forward portion 8^a of the deflector is preferably provided with a series of ventilating notches 13 in its sides which lie adjacent to or come in contact with the side walls of the iron. The deflector is substantially centrally disposed within the iron and its side walls 14 are preferably spaced from the side walls of the iron as shown in Figs. 2 and 3, and the deflector walls are preferably notched on the bottom, as indicated at 14^a; the notches being so placed and spaced as to be substantially intermediate the apertures 4 adjacent the bottom of the iron. These several apertures and notches in the walls of the iron and in the walls of the deflector serve to insure the presence of a sufficient quantity of air to support combustion, while the apertures adjacent the top of the iron insure proper vent for excess of heat and products of combustion.

Secured to the rear open end of the body of the iron is a burner comprising a shell 15, having a portion 16 which may engage a notch 17 in the base of the iron; said shell having an upper projection 18 with a recess or socket 19 for engagement by a set screw 20 carried by the top wall of the iron body. The chamber 21 of this burner shell may be and preferably is substantially egg-shaped, as clearly indicated by the sectional views of the same, and is provided at its inner end 105 adjacent the guard with a wire screen or

flame surface 22, held in place by a retaining ring 22^a. This retaining ring extends into the chamber 21, holding the screen 22 in place and forms an annular outlet passage 5 beyond said screen. This wall of this burner shell is provided with the usual air inlet spaces communicating with the chamber of the iron and indicated at 23; being disposed on opposite sides of said burner shell.

10 Carried by the burner structure is a gas supply tube 25, having a hose connecting nipple 26; said tube being notched or slotted at 27 for the inlet of air to mix with the gas and support combustion, and with a valve 15 sleeve 28 to adjust the area of the openings formed by said slots or notches, which sleeve is confined against extreme movement by a set screw or other stop 29.

The gas supply tube is provided with an 20 apertured wall 30 having a needle valve 31, which may be of any approved type, controlled by a screw member 32, having a cam 33 for action upon the lower end of said valve when it is desired to close the same; 25 a spring 34 being employed to open the valve when the cam is disengaged therefrom. In the usual burner devices for gas heated irons, this valve is arranged to entirely close the gas inlet opening, and is operated when 30 it is desired to cut down or entirely cut off the supply of gas after the iron heats up.

It is highly dangerous to throw the gas pressure onto the rubber tube employed as a conduit for the gas, and insurance underwriters object to the practice. To obviate any danger, I flatten the point of the needle valve, as indicated at 35, so that when it is seated it can not entirely close the aperture in the wall 30, and hence enough gas will 40 pass to form a pilot flame. When this pilot flame is in use, the supply of air entering via the slots 27 may be cut down by means of the sleeve valve 28.

I claim:

45 1. In a gas heated iron, the combination of a body portion having a plurality of apertures in its side walls adjacent the top of the same, a plurality of apertures in said side walls adjacent the bottom of the same and 50 disposed at the rear of said body, said latter apertures opening outwardly below the plane of the inner surface of the iron bottom, a burner connected to the rear of said iron, and a flame deflector detachably 55 mounted within the iron, said flame deflector having a downwardly curved forward end disposed adjacent the toe of the iron and notches forming apertures for the passage 60 of air to the interior of the flame deflector adjacent the rear apertures in the body of the iron.

2. In a gas heated iron, the combination of a body portion having a plurality of apertures adjacent the top of the same and a plurality 65 of apertures adjacent the bottom of

the same and disposed at the rear of said body, a burner detachably connected to the rear of said iron, a flame deflector detachably mounted within the iron, said flame deflector having notches forming apertures for 70 the passage of air to the interior of the same adjacent the rear apertures in the body of the iron.

3. In a gas heated iron, the combination of a body portion with side walls having a 75 plurality of apertures at top and bottom of the same, the bottom apertures being disposed at the rear of said body and opening outwardly below the plane of the inner surface of the iron bottom, a burner connected 80 to the rear of said iron, and a flame deflector detachably mounted within the iron, said flame deflector having a forward downwardly curved end in engagement with the side walls of the iron, said end being notched 85 and forming with the side walls of the iron apertures for the passage of heated air adjacent the forward upper apertures in the wall of the iron, and said flame deflector having notches forming apertures for the passage of 90 air to the interior of the same adjacent the rear apertures in the body of the iron.

4. In a gas heated sad iron, the combination of a body portion having a plurality of apertures adjacent the top of the same, 95 a plurality of apertures adjacent the bottom of the same and disposed at the rear of said body, a burner connected to the rear of said iron, a flame deflector detachably mounted within the iron, said flame deflector having 100 notches forming apertures for the passage of air to the interior of the same adjacent the rear apertures of the body portion and having a forward downwardly curved end in engagement with the side walls of the iron, 105 said end being notched at the sides engaging said walls.

5. The combination, in a gas heated iron, of an apertured body portion, a burner detachably connected to the rear of the same, said burner having an enlarged mixing chamber with an enlarged outlet providing a flame of large area, means for delivering gas to said burner, a wire screen for said burner, said screen being disposed within the burner, and means extending into the burner and forming an annular outlet passage beyond the screen for confining the latter in place, said mixing chamber having a greater cross-sectional area than the flame 110 outlet leading therefrom.

6. In a gas heated iron, the combination of a body portion having side walls with a plurality of apertures adjacent the top and bottom of the same, said bottom apertures 115 being disposed near the rear of said body, a burner connected to the rear of said iron, and a flame deflector detachably mounted within the iron, said flame deflector having side walls spaced from the side walls of the 120

iron for a portion of its length and a downwardly curved forward end disposed adjacent the toe of the iron, the walls of said deflector having notches at the bottom edges forming ventilating openings adjacent the bottom openings of the iron body.

In testimony whereof, I have signed my

name to this specification, in the presence of two subscribing witnesses.

HORACE L. BREWER.
